FUNNEL

Antonio M. Carvalho, Newark, N. J.

Application November 24, 1931, Serial No. 576,989

2 Claims. (Cl. 226—36)

This invention relates to funnels, and the object of the invention is to provide a device of the class specified, having means for automatically controlling the level of fluid poured into a vessel or container and for preventing the discharge of any excess fluid contained in the funnel in the operation of moving the funnel from a filled vessel to another vessel to be filled; a further object being to provide a funnel of the class specified, having an elongated discharge tube, the length of which in proportion to the size of the bottle or vessel to be filled, will govern the height of the fluid desired in filling the bottle or vessel, and further to the provision of a valve for closing the communication between said tube and the body of the funnel when the funnel is removed from a filled container; a further object being to provide a funnel with a plurality of telescoping tubes whereby the length of the tubes may be regulated to suit containers of different sizes and dimensions; and with these and other objects in view, the invention consists in a funnel of the class and for the purpose specified, which is simple in construction, efficient in use, and which is constructed as hereinafter described and claimed.

The invention is fully disclosed in the following specification, of which the accompanying drawing forms a part, in which the separate parts of my improvements are designated by suitable reference characters in each of the views, and in which:

Fig. 1 is a sectional view through a funnel made according to my invention indicating one method of its use.

Fig. 2 is a sectional view through the funnel at right angles to that shown in Fig. 1, with parts in a different position.

Fig. 3 is a plan view of the funnel shown in Fig. 1, with part of the construction broken away and in section; and,

Fig. 4 is a side view of the funnel, showing a modification.

In the drawing, I have shown at 5 a funnel body of conventional form and contour having a relatively wide bottom wall 6 terminating centrally in a depending tube 7, the wall 6 being tapered downwardly in the direction of the tube 7 to insure discharge of the fluid introduced into the funnel 5. The bottom wall 6 joins the outwardly and upwardly flaring side wall 8 of the funnel in a short vertical wall 9, in which a substantially cone-shaped guard 10 is mounted, the lower end of said guard fitting snugly with-

in the wall 9 and having thereabove a plurality of apertures 11 for placing the interior of the guard 10 in communication with the chamber 12 of the funnel. In the construction shown, the upper end of the funnel 5 or the wall 8 thereof terminates in an annular band 13 having a vertically disposed wall, but it will be understood that my invention is not limited to the specific contour of the funnel body herein disclosed.

A valve 14 is mounted to move toward and from the upper end of the tube 7 to control the discharge of the fluid from the chamber 12 into and through the tube 7, said valve having a beveled portion 14a which seats in the upper end of the tube 7 in accomplishing this result. The valve 14 has a long, thin stem 15 which projects upwardly into the guard 10 and is connected centrally with the crosshead 16 of a U-shaped guide member having depending rods 17 which operate in tubular portions 18 secured to the bottom wall 6 at opposite sides of the tube 7 as seen in Fig. 1 of the drawing. The rods 17 pass through the bottom wall 6 and are coupled with a disk 19, by means of which the valve 14 is moved into raised position in the operation of placing the funnel upon a bottle, vessel or other container, such for example as the bottle 20 indicated in Fig. 1 of the drawing. A strap 21 is also preferably employed to brace the upper ends of the guide tubes 18.

The construction shown in Fig. 4 of the drawing differs from that shown in the other figures simply in providing a tube 7a, shorter than the tube 7, and two other tubes 22 and 23, the tube 22 telescoping with respect to the tube 7a, and the tube 23 telescoping with respect to the tube 22. With this construction, the length of the discharge tube from the funnel 5 may be varied to suit the size, dimensions and contour of the container, it being understood at this time that the contour of the neck portion of the container will govern to a large degree the length of the tube required to properly fill the same.

The operation of my improved device will be readily understood from the foregoing description when taken in connection with the accompanying drawing and the following statement. In the normal position of the funnel, that is to say, when the funnel is detached, the valve 14 is in seated position and the plate 19 is arranged in spaced relation with respect to the bottom wall 6 of the funnel, the parts maintaining this position by gravity, the weight of the valve and its com-

panion parts being sufficient to maintain this position in the various uses of the device.

In the operation of filling a container, such for example as the bottle 20, shown in Fig. 1, the funnel is placed upon the top of the bottle, in which operation, the plate 19 is automatically raised into abutment with the bottom wall 6 of the funnel. In like manner, the valve 14 is raised to open the communication between the funnel

10 and the tube 7-7a through the openings 11 formed in the guard 10. At this time, it will be understood that the guard 10 is detachable with respect to the funnel, and may be removed in the use thereof, the guard being employed to prevent 15 injury to the valve stem and its guide rods and guide tubes. The fluid to be transmitted to the chamber of the bottle 10 is now poured into the funnel chamber 12 and passes downwardly through the tube 7-7a and into the bottle.

20 By virtue of the length of the tube 7 with respect to the particular bottle to be filled and the restricted passage between the valve 14 and upper end of tube 7, the fluid will travel up to and automatically stop at the level indicated at 24 in Fig. 25 1 of the drawing, which will be substantially the desired level to be maintained in the container, or in other words which will represent the desired fluid content to be placed in the container. It will be understood that this operation takes place regardless of the amount of fluid still remaining in 30 the funnel which is of predetermined size. It will also be apparent that the restricted passage as shown in Fig. 1 of the drawing may be considered exaggerated for clearness of illustration.

35 At this time, the funnel is removed from the bottle 20 and in this operation, the plate 19 automatically drops by gravity as does also the valve 14 which seats upon the upper end of the tube 7-7a and shuts off the communication between the 40 chamber 12 of the funnel and said tube. Thus, no fluid will be discharged from the tube 7 in moving the funnel from the filled bottle 20 to another similar bottle, next to be filled.

45 With a funnel of this construction, the operation of filling bottles, vessels, cans or other containers of various kinds and classes with the required fluid contents, may be accomplished accurately and without the loss of any of the fluid. A funnel of this type is especially desirable in filling 50 containers with costly fluids, such for example, as expensive perfumes.

55 For commercial use, where bottles or containers are all of a similar size and contour, it will be understood that a funnel of the desired capacity and tube length will be provided. But, for the 60 home and for uses where the size and dimensions of the containers will vary from time to time, a funnel such as that shown in Fig. 4 provided with the adjustable or telescoping tubular body will be employed. The same result can be accomplished by using two tubes, one detachable with respect to the other, the detachable tube varying in its length to suit containers of different standard sizes.

It will be understood that while I have shown certain details of construction for carrying my invention into effect, that I am not necessarily limited to these details and various changes in and modifications of the construction herein shown and described may be made within the scope of the appended claims without departing from the spirit of my invention or sacrificing its advantages.

Having fully described my invention, what I 10 claim as new and desire to secure by Letters Patent, is:

1. A funnel of the class described comprising a conical body having a relatively large, flat bottom wall having a projecting discharge tube 15 centrally thereof, a plate slidably engaging the tube outwardly of the bottom wall and including a rod passing upwardly through a guide tube extending from the bottom wall upwardly into the funnel body, the discharge tube opening into the 20 funnel body centrally thereof, a valve supported on said rod and cooperating with the upper end of the discharge tube to control the transmission of fluid from the funnel body into and through said tube, said valve having a tapered portion 25 seating in said tube and a reduced straight wall part at the lower end thereof maintained in the tube when the valve is in raised position to guide and control the flow of fluid into said tube from the funnel body, the funnel body having a shoulder portion 30 formed between the flat bottom wall and conical wall thereof and a thimble-shaped guard mounted upon and enclosing the valve rod and tubular guide therefor and seating in the shoulder portion of the funnel body.

35 2. A funnel of the class described comprising a conical body having a relatively large, flat bottom wall having a projecting discharge tube centrally thereof, a plate slidably engaging the tube outwardly of the bottom wall and including a rod 40 passing upwardly through a guide tube extending from the bottom wall upwardly into the funnel body, the discharge tube opening into the funnel body centrally thereof, a valve supported on said rod and cooperating with the upper end of the 45 discharge tube to control the transmission of fluid from the funnel body into and through said tube, said valve having a tapered portion seating in said tube and a reduced straight wall part at the lower end thereof maintained in the tube when the valve is in raised position to guide and control the flow of fluid into said tube from the funnel body, the funnel body having a shoulder portion 50 formed between the flat bottom wall and conical wall thereof and a thimble-shaped guard mounted upon and enclosing the valve rod and tubular guide therefor and seating in the shoulder portion of the funnel body, and the lower portion 55 of the guard having circumferentially spaced apertures placing the chamber of the funnel body in communication with the interior of said guard and said discharge tube.

ANTONIO M. CARVALHO.
